UNITED STATES PATENT OFFICE.

JOHN F. CUMMING, OF WORCESTER, MASSACHUSETTS, ASSIGNOR TO THE AMERICAN TYPE FOUNDERS COMPANY, OF NEWARK, NEW JERSEY.

DESIGN FOR A FONT OF PRINTING-TYPE.

SPECIFICATION forming part of Design No. 29,480, dated October 11, 1898.

Application filed November 11, 1896. Serial No. 611,765. Term of patent 7 years.

● To all whom it may concern:

Be it known that I, JOHN F. CUMMING, a citizen of the United States, and a resident of Worcester, Massachusetts, have invented and produced a certain new and useful Design for Type, of which the following is a specification.

My design for Italic type is clearly illustrated in the accompanying drawing.

○ The essential feature of the design is the Italic letter having a heavy face, the letters of the upper case having heavy serifs and cross-bars, giving the peculiar effect illustrated in the typographical impression.

5 The letters A, D, E, F, H, I, J, K, L, M, N, P, R, T, U, V, W, X, and Y of the upper case have the heavy serifs with squared ends. The letters C and G have the peculiar curve shown. The letter J has the lower end curved and tapered. The letter Q is similar to the letter O, with the exception that the letter Q has a scroll underneath connected by a short neck. The lower right-hand line of the letter R is curved and slightly tapered.

The letters of the lower case have a slight 25 Old-English effect and are in keeping with the letters of the upper case.

The numerals are also in keeping with the letters of the upper and lower cases.

I claim—

The design for a font of type, as herein shown and described.

In testimony whereof I have signed my name to this specification in the presence of two subscribing witnesses.
